AUTOMATIC RECORD-CHANGING APPARATUS

Fritz Kahl, Fort Wayne, and Ortis C. Booher, Huntington, Ind., assignors to Farnsworth Television and Radio Corporation, a corporation of Delaware

Continuation of application Serial No. 348,576, July 30, 1940. This application July 27, 1942, Serial No. 452,410

2 Claims. (CL 274—10)

This application is a continuation of our application Serial No. 348,576 filed July 30, 1940. It relates to phonograph apparatus and more particularly to improved mechanism for controlling the positioning of the pickup arm in phonograph apparatus.

An object of the present invention is to provide control mechanism for positioning the pickup arm of improved and simplified construction.

A further object of the present invention is to provide improved control mechanism for positioning the pickup arm for engaging the initial playing groove of various sized records.

A further object of the invention is to provide control mechanism for the positioning of the pickup arm for engaging the initial playing groove of various sized records which is automatically adjusted by the movement of record supporting mechanism.

A further object of the invention is to provide control mechanism for positioning the pickup arm for engaging the initial playing groove of various sized records, which control mechanism is automatically adjusted when the record changing apparatus is adapted to handle records of different sizes.

In accordance with the present invention there is provided an automatic phonograph which includes record-changing apparatus, a turntable and a pickup arm with a stylus for reproducing a record on the turntable. The automatic phonograph also includes operating means associated with the pickup arm for moving the pickup laterally relative to the turntable. The operating means is adapted to be adjusted to a plurality of positions for positioning the stylus of the pickup arm over the initial playing groove of the record in playing position on the turntable. Adjusting means is operatively associated with the operating means for adjusting the operating means to its plurality of positions. Means also is provided which is operatively associated with the adjusting means for adapting the record-changing apparatus for handling at different times records of different predetermined sizes. Upon the adaption of the record-changing apparatus for handling records of predetermined size by the last mentioned means, the operating means is automatically adjusted to position the stylus of the pickup arm over the initial playing groove of the record which the record-changing apparatus is adapted to handle.

For a better understanding of the invention together with further objects thereof, reference is made to the following description taken in con-

nection with the accompanying drawings, and its scope will be pointed out in the appended claims.

In the accompanying drawings Fig. 1 is a top plan view of the apparatus;

Fig. 2 is a side elevation view of the apparatus in Fig. 1;

Fig. 3 is a rear elevation view of the apparatus in Fig. 1;

Fig. 4 is a bottom plan view of the apparatus below the base plate of the automatic phonograph;

Fig. 5 is a view of a friction clutch assembly used in the apparatus.

Referring now particularly to Fig. 1 of the drawings, the invention as illustrated is embodied in an automatic phonograph which includes a base plate 15. A turntable 16 is mounted on the base plate 15 to rotate relative thereto, and is adapted to support one or more records 17 thereon. The top record on the turntable 16 is in playing position and is ready to be reproduced. A stack of records 18 (Fig. 2) is supported above the turntable in a manner to be described hereafter so that the lowermost record of the stack may be moved into playing position on the turntable 16. A pickup or reproducer 19 is supported at one end of a pickup arm 20 which is connected at its opposite end to a shaft 21 (Figs. 2 and 3). The shaft 21 extends downwardly in a pedestal 22 and is rotatable relative thereto. The pedestal 22 is mounted on top of the base plate 15 and adjacent to the turntable 16. The pickup arm 20 is mounted to rotate about the vertical axis of the shaft 21 to move across the face of a record on the turntable as the stylus of the reproducer 19 follows the groove of the record.

The stack of records 18 is positioned above the turntable centrally relative thereto by a pin 23 extending downwardly from a plate 24. The plate 24 is pivotally supported at its opposite end upon a bracket 25 which is connected to the base plate 15 and which extends upwardly therefrom.

The stack of records 18 is supported on shelves 26 and 27A or 27B. The shelf 26 is supported on the bracket 25 and the shelves 27A and 27B are supported by the bracket 25. When the records supported above the turntable are ten-inch records or records of relatively small diameter, they are supported by edge 26A of the shelf 26 and the shelf 27A. When the stack of records supported above the turntable consists of twelve-inch records or records of relatively large diameter, they are supported by edge 26B of the shelf 26 and the shelf 27B. The shelf 26 with its edges 26A and 26B is clearly shown in Fig. 1.

The shelf 26 is connected to the upper end of a shaft 29. This assembly is supported by a bracket 28. The shelf 26 and the shaft 29 are mounted in the bracket 28 so that they are adapted to rotate relative thereto. Thus, the shelf 26 may be rotated to different positions for supporting records of different diameters, as will be described more fully hereafter. When the shelf 26 is in the position shown in Fig. 1, it is adapted to support ten-inch records. When the shelf 26 is rotated 90° in a counterclockwise direction from the position shown in Fig. 1, it is adapted to support twelve-inch records.

The shelves 27A and 27B are adapted to support ten-inch and twelve-inch records respectively. The shelf 27B is supported directly upon uprights or pins 30 (Fig. 3) which are slidably mounted and guided by a member 31 which may be an integral part of the bracket 28. The shelf 27A is pivotally supported on a rod 32 which is secured to a pair of ears 33 extending upwardly from the shelf 27B. The pins 30 with the supporting shelves 27A and 27B carried thereby, are normally held in an uppermost position shown in Fig. 3 by springs 34. When the pins 30 are held in an uppermost position, they are adapted to maintain the stack of supported records free of a record releasing member and spindle to be described hereafter.

The lower ends of the pins 30 which extend through and below the base plate 15 are connected by a bar 35 (Fig. 3) which is provided with a roller 36 (Fig. 4). The roller 36 is positioned so that it is capable of being engaged and actuated by a movable cam assembly, which will be described hereafter, for lowering the bar 35 against the tension of the springs 34 to lower the shelves 27A and 27B when the lowermost supported record is to be released to playing position upon the turntable.

A spindle 38 affixed to the turntable 16 to rotate therewith extends upwardly from the turntable. The lower portion 38A of the spindle, which extends upwardly to the height to which records may accumulate upon the turntable, performs the function of centering records on the turntable. Above the portion 38A the spindle 38 is prolonged to form an eccentric portion 38B terminating in a reduced portion 38C which is formed by notching the upper end of the spindle. The notching of the spindle forms a shoulder 38D. The reduced portion 38C of the spindle lies immediately under the overhead pin 23 and is located eccentrically of the axis of said pin. The reduced portion 38C is spaced from the pin 23 a distance less than the thickness of one record, so that, when a record is moved from the supporting shelves, said record is certain of engaging said reduced portion. The reduced portion 38C and the eccentric portion 38B of the spindle 38 rotate with the turntable eccentrically of its axis of rotation and eccentrically of the axis of the pin 23.

The stack of supported records 18 normally is carried by the supporting shelves in a plane above the reduced portion 38C of the spindle so as not to be engaged by the reduced portion. When the shelves 27A and 27B are lowered by the downward movement of the pins 30, the lowermost supported record moves into the path of the portion 38C after which this record is moved to playing position upon the turntable. A more detailed description of the movement of the supported record to playing position upon the

turntable appears in our parent application Serial No. 348,576.

The mechanism for driving the automatic phonograph, including the record-changing apparatus, includes an electric motor 40 which is provided with a shaft 41. The motor 40 is connected to the bottom of the base plate 15 in a suitable manner such as is shown in Fig. 2 of the drawings. The shaft 41 extends above the base plate and is adapted to engage a friction wheel 43, shown in Fig. 2, by dotted lines under the left-hand flange of the turntable. The friction wheel 43 is rotatably mounted above the base plate 15 and is in engagement with the shaft 41 and the flanged portion of the turntable 16. When the electric circuit to the motor is closed, shaft 41 drives, through the friction wheel 43, the turntable 16 and the turntable shaft 42. The shaft 42 is suitably connected to the base plate 15, preferably in the manner shown in Fig. 2. The spindle 38, previously described, is fixed to the upper end of the shaft 42 and rotates therewith. Below the base plate 15, the shaft 42 has affixed thereto a pinion gear 44 adapted to mesh with a cam gear 46. The cam gear 46 is rotatably mounted from the bottom of the base plate on a shaft 47, preferably in the manner shown in Figs. 2 and 4. Several teeth are removed from the cam gear 46 at 48 to form a mutilated portion. The mutilated portion 48 serves the purpose of breaking the driving connection between the cam gear 46 and the pinion gear 44.

The shaft 42 is provided with a radially extending pin or projection 49, preferably mounted immediately above the pinion gear 44. The pin 49 is adapted to engage a pivotal lever 50 mounted on the upper surface of the cam gear 46 when the pivotal lever is moved into its path. During the playing of a record on the turntable the pivotal lever 50 is maintained out of the path of the pin 49 by a horizontally pivoted lever 52 which is affixed to the base plate 15 at 53. The lever 52 is adapted to be actuated by a tripping mechanism to be described hereafter, which in turn is actuated by the pickup arm 20. In moving toward the center of a record, the pickup arm 20 rotates the shaft 21. The shaft 21 has secured to it a clutch mechanism 54, the detailed construction of which will be described hereafter, which frictionally engages a lever 55. By this connection of the lever 55 to the clutch 54, the lever 55 is adapted to rotate with the shaft 21 and also is adapted to rotate relative to the shaft 21.

Thus, as a record is being played and the pickup arm 20 moves toward the center of the record, the clutch mechanism 54 moving with the shaft 21, moves the lever 55 in a counterclockwise direction (Fig. 4). The lever 55 is adapted to engage the side of a lever 56, one end of which is connected to the shaft 21 to move freely relative thereto. The free end of the lever 56 is preferably turned downwardly and is adapted to engage the lower end of the lever 52.

Each time the cam gear 46 completes a revolution, one end of the lever 52, previously described, engages one end of the lever 56 and moves it out of the path of the pin 49.

As the stylus of the pickup arm 20 approaches a tripping groove of a record in playing position on the turntable, it moves the levers 55, 56 and 52 in a counterclockwise direction (Fig. 4). One end of the lever 52 carries a spring 57 which lies in the path of a cam 58 which is fixed to and rotates with the shaft 42. The cam 58 peri-

odically strikes the spring 57 and moves the lever 52 and with it the levers 55 and 56 in a clockwise direction (Fig. 4), the levers 55 and 56 changing their position relative to the pickup arm shaft 21 by virtue of their relationship to the shaft 21.

When the stylus of the pickup arm 20 moves into a tripping groove of the record that is being played, the pickup arm during a revolution of the turntable is moved more than the distance that it was moved when it was tracking the playing groove of the record on the turntable. The abnormal movement of the pickup arm 20 moves the levers 55 and 56 a corresponding abnormal distance. The abnormal movement of the lever 56 moves the lever 52 in a clockwise direction (Fig. 4) to disengage the lever 50 and to permit it to initiate a record-changing cycle. If the clutch 54 is properly set, which setting will be more clearly described when this clutch is described in detail, the tripping mechanism will also operate when the pickup arm reaches a predetermined position from the center of the turntable. Under this condition when the pickup arm reaches the predetermined position from the center of the turntable, an ear 60 will come into engagement with an ear 61. Thereafter, the lever 55 can be moved in a clockwise direction (Fig. 4) only against the biasing action of a spring 62, as will presently be shown in greater detail when the detailed construction of the clutch 54 is described. Thus, when the cam 58 strikes the spring 57 after the pickup arm has reached the predetermined position from the center of the turntable, the levers 55, 56 and 52 are moved in a clockwise direction (Fig. 4) creating a tension on the spring 62. Immediately after the cam 58 passes out of engagement with the spring 57, the levers 55, 56 and 52 are returned in a counterclockwise direction by the tension on the spring 62. The return movement is sufficiently great so that the lever 52 is moved out of engagement with the lever 50 which permits it to initiate a record-changing cycle.

The fixed stop 63 is secured to the bottom of the base plate 15. The stop 63 has an end 64 turned at right angles thereto, and is positioned in the path of the movement of the lever 55. As the pickup arm 20 is swung to its outwardmost position during the record-changing cycle, it moves the lever 55 in a clockwise direction (Fig. 4) into engagement with the end 64 of the member 63. The engagement of the lever 55 with the end 64 occurs before the pickup arm 20 is swung toward its outwardmost position. Thus, after the lever 55 and the stop 63 are in engagement with each other and the pickup arm 20 continues to move outwardly, the lever 55 adjusts its angular position relative to the pickup arm through the slipping connection provided by the clutch 54. As a result, the lever 55 is positioned well forward relative to the pickup arm as the pickup arm is returned to the initial playing groove of a record on the turntable and insures positive engagement of the levers 55, 56 and 52 prior to the time when the stylus of the pickup arm 20 reaches the tripping groove of a record or a predetermined position from the center of the turntable.

Various parts of the clutch 54 are shown in Fig. 5. A flanged sleeve 66 is fixed to the pickup arm shaft 21 in a suitable manner so that the ear 60 engages the ear 61 when the pickup arm reaches a predetermined position from the

center of the turntable. The particular predetermined position at which the ears 60 and 61 come into engagement with each other depends on the relationship of the clutch 54 to the shaft 21. The pickup arm 20 is also fixed to the pickup arm shaft 21 to move therewith. A plate 69, with the lever 55 and the ear 60 extending therefrom, is mounted in frictional relationship with the upper surface of the flange portion of the member 66. A suitable frictional washer 70, preferably of a fibrous material, is slipped over the plate 69 and around the sleeve of the member 66. A plate 71 with the turned-down ear 61 is placed over the fiber washer 70 and around the sleeve of the member 66. The ear 60 and the ear 61 are so related that the clockwise movement (Fig. 4) of the plate 69 and the lever 55 will bring the ear 60 into engagement with the ear 61. A spring washer 72 is placed over the plate 71 and around the sleeve of the member 66. A flanged cover member 73 is screwed on the sleeve of the member 66 so that the bottom of the flanged portion of the cover member 73 rests on the spring washer 72. Pressure which is applied to the rest of the members of the clutch 54 is adjustable so that the spring washer 72 maintains an even frictional engagement between the plate 71 and the fiber washer 70. The spring 62 has one end connected to the peripheral wall of the member 66 and the other end to the turned-down ear 61. Thus, it will be readily seen that when the ear 60 engages and moves the ear 61, a tension will be created in the spring 62. As has been explained before, the tension created in the spring 62 will initiate the operation of the tripping mechanism when the pickup arm reaches a predetermined position from the center of the turntable.

Upon the release of the lever 50 from engagement with the lever 52, projection 49 engages one end of the lever 50 and moves it and therewith the cam gear 46 far enough to bring the teeth on the periphery of the cam gear 46 into engagement with the teeth of the pinion gear 44, after which the cam gear 46 is rotated through one revolution. After one revolution the cam gear 46 will come to rest in the position shown in Fig. 4.

The cam surfaces on the cam gear 46 perform several functions. The cam surface 15 performs the first function. An arm 76 is pivotally mounted intermediate its ends by means of a bracket 77 to the underside of the base plate 15. The arm 76 carries at one end a roller 78 which is biased into engagement with the cam surface 15 by a spring 80 suitably connected to the bracket 77. As the roller 78 follows the cam surface 15, it moves the left-hand end (Fig. 4) of the arm 76 upwardly. This movement in turn raises the pin 81 (Fig. 3) vertically in the hollow shaft 21. The upper end of the pin engages the underside of the pickup arm 20 to raise it.

The next function performed by the cam surfaces on the cam gear 46 is to swing the pickup arm 20 beyond the turntable to its outwardmost position. For this purpose there is provided a lever 82 (Figs. 3 and 4) which is affixed to the lower end of the shaft 21. At the free end of the lever 82, there is provided a pin 83. Lateral movement of the lever 82 affects a corresponding movement to the pickup arm 20 and vice versa. The pin 83 at the free end of the lever 82 is adapted to move within an aperture 84 located in the heel of an L-shaped lever 85.

(Fig. 4) which is pivotally mounted at 86 to the underside of the base plate 15. The aperture 84 is sufficiently large to permit the pin 83 of the lever 82 to move freely so as not to hinder the movement of the pickup arm while playing a record on the turntable. The toe 87 of the L-shaped lever 85 engages a cam surface 88 provided on the cam gear 46. The toe 87 is continuously biased toward the cam surface 88 by a spring 89. The spring 89 is fixed to the lever 85 and to the suitable fixed object as shown in Fig. 4. After the pickup arm 20 has been raised from the surface of the record on the turntable in the manner previously described, and as the cam gear 46 continues to rotate, the cam surface 88 moves the L-shaped lever 85 in a counter-clockwise direction (Fig. 4) about its connection to the base plate and causes the right-hand side (Fig. 4) of the aperture 84 to engage and drive before it the pin 83. The movement of the pin 83 moves therewith the lever 82, the shaft 21 and the pickup arm 20 in a radial direction relative to the turntable and away from the center of the turntable. The cam surface 88 is so shaped that the L-shaped lever 85 ceases its counterclockwise rotation (Fig. 4) at a time when the pickup arm 20 has been moved to its outwardmost position.

After the pickup arm 20 has been swung to its outwardmost position another record is moved into playing position upon the turntable. The lowermost supported record on the shelves 26 and 27A or 27B is moved by lowering the shelves 27A or 27B until the lowermost supported record is engaged by the reduced portion 38C of the spindle 38. This movement of the shelves 27A or 27B is affected by the engagement of the cam surface 88 (Fig. 4) with the roller 36 affixed to the bar 35 to lower the shelves 27A or 27B. After the lowermost supported record has been moved out of engagement with either the shelves 27A or 27B, the cam surface 88 moves out of engagement with the roller 36 and permits the springs 34 to return the shelves 27A and 27B to their normal positions so that the rest of the supported records will be free of the reduced portion 38C.

The cam gear 46 has by this time rotated sufficiently far so that the cam surface 88 allows the L-shaped lever 85 to move in a clockwise direction (Fig. 4) under the biasing action of the spring 89 to return the pickup arm 20 to a position where the stylus of the pickup arm is over the initial playing groove of the record in playing position upon the turntable.

At this time the cam surface 75 has rotated to the point where the arm 16 permits the pin 81 to move vertically downward, thus, allowing the stylus of the pickup arm 20 to be lowered into engagement with record in playing position upon the turntable. Immediately thereafter the cam gear comes to rest in the position shown in Fig. 4 of the drawings, and the reproduction of the record in playing position upon the turntable takes place.

As shown in Figs. 2 and 4, the shelf 26, which is fixed to the upper end of the shaft 29 and is supported by the bracket 28, is adapted to be locked in a plurality of selected positions by a locking cam 93 secured to the lower end of the shaft 29. The cam 93 is provided with notches 94, 95 and 96 which are adapted to be engaged by a pin 97 provided on the free end of a lever 98. Lever 98 is pivotally connected intermediate its ends at 98 to the bottom of the base plate 15.

A spring 100, which is fixed to the lever 98 and a suitable fixed object as shown in Fig. 4, normally biases the pin 97 into continuous engagement with one of the notches 94, 95 and 96. When the notch 94 engages the pin 97, the shelf 26 is locked in position to support ten-inch records. When the notch 95 engages the pin 97, the shelf 26 is locked in position to support twelve-inch records, and when the notch 96 engages the pin 97, the shelf 26 is locked in non-supporting position thus allowing the easy removal of played records from the turntable. The opposite end of the lever 98 extends over the end of the lever 85 on which is provided a set screw 101. As the lever 85 rotates about the point 86, the set screw is adapted to come into engagement with the end of the lever 98 and to be stopped thereby. When the apparatus being described is set to handle ten-inch records, the lever 85 is permitted to rotate far enough in a clockwise direction (Fig. 4) so that the toe 87 engages the cam portion 88 in the manner shown in Fig. 4 just before the end of a record-changing cycle. The levers 85 and 82 are in such adjustment that when the toe 87 and the cam portion 88 are in engagement as shown in Fig. 4, the stylus of the pickup arm 20 is over the initial playing groove of a ten-inch record in playing position upon the turntable 16. When the apparatus being described is in adjustment for handling twelve-inch records, the lever 98 does not permit the lever 85 to rotate in a clockwise direction (Fig. 4) as far as it rotated when the apparatus was in adjustment for the handling of ten-inch records. As a result of this, the lever 85 is stopped by the lever 98 before the toe 87 engages the cam portion 88. Thus, the stylus of the pickup arm is positioned over the initial playing groove of a twelve-inch record in playing position upon the turntable 16. The adjustable screw 101 on the end of lever 85 is provided for changing slightly the positioning of the pickup arm over a twelve-inch record. The inward movement of the adjusting screw 101 will change the positioning with the stylus of the pickup arm outwardly relative to the center of the turntable, and the outward movement of the adjusting screw 101 will change the positioning of the stylus of the pickup arm 20 inwardly relative to the center of the turntable.

Thus, it is evident that the manually positioning of the shelf 26 for supporting either a stack of ten-inch or twelve-inch records, automatically sets the pickup arm control mechanism for positioning the pickup arm in a proper position to engage the initial playing groove of the size of record that is being handled by the mechanism being described.

In addition to the automatic tripping mechanism previously described, there is also provided a manual trip lever 102 (Fig. 4) pivotally mounted on the underside of the base plate 15. The lower end 103 of the lever 102 is bent to extend upwardly through a slotted aperture 104 (Fig. 1) in the base plate 15. To this bent end 103 is fixed knob 105 (Figs. 1 and 2). The lever 102 is normally biased by a spring 106 out of engagement with the turned-down lower end of the lever 82. However, the lever 102 may be pivoted manually to engage the lower end of the lever 82 for moving its upper end to disengage the lever 88 whereby, as has been previously described, the gear 46 is brought into driving engagement with the pinion 44 to carry out a record-changing cycle.

The general mode of operation will now be described. After a stack of records has been placed upon the shelves 26 and 27A or 27B associated with the brackets 25 and 28 respectively, and a record has been placed in playing position upon the turntable 16, the pickup arm 20 is moved manually to place the stylus in the initial playing groove of the record on the turntable.

The pickup arm 20 moves inwardly as the stylus follows the playing groove of the record and eventually reaches the tripping groove or a predetermined position from the center of the turntable where the automatic tripping mechanism is actuated by the movement of the levers 55, 56 and 52 (Fig. 4) responsive to the movement of the pickup arm 20, whereby the lever 52 is disengaged from the lever 50 and the lever 50 moves in a vertical plane into the path of the pin 49 provided on the shaft 42.

Engagement of the pin 49 with the lever 50 causes the cam gear 46 to be rotated until its teeth mesh with the teeth of the pinion gear 44, after which the cam gear 46 is driven by the pinion gear 44 through a record-changing cycle.

As the cam gear 46 rotates, the cam surface 15 (Fig. 4) moves the arm 76 and raises the pickup arm off of the played record.

Continued movement of the cam gear causes the cam surface 88 (Fig. 4) to move the L-shaped lever 85, and therewith the lever 82, to swing the pickup arm 20 to its outwardmost position.

Shortly thereafter, the cam surface 90 (Fig. 4) engages the roller 36 which forces the bar 35 downwardly, thus lowering the shelves 27A and 27B so that the lowermost supported record is moved on the shoulder 38D of the spindle 38. The rotation of the spindle 38 moves this record from the shelves 27A or 27B. Immediately thereafter the springs 34 raise the shelves 27A and 27B to their normal position, thereby raising the rest of the stack of unplayed records out of engagement with said spindle. The record on the shoulder 38D of said spindle is thereafter moved by the rotation of the spindle 38 to playing position on the turntable.

The cam gear 46 has by this time rotated sufficiently far so that the cam surface 88 (Fig. 4) allows the L-shaped lever 85 to move clockwise (Fig. 4) under the biasing action of the spring 89 to return the pickup arm to a position where the stylus is over the initial playing groove of the record in playing position upon the turntable.

At this time, the cam surface 76 (Fig. 4) has rotated to the point where the arm 76 permits the stylus of the pickup arm 20 to be lowered into engagement with the record just placed on the turntable. Immediately thereafter, the cam gear 46 comes to rest in the position shown in Fig. 4 and the playing of the record recently placed upon the turntable takes place.

The next and following cycles of the automatic operations are initiated by the automatic tripping mechanism each time the stylus in the reproducer moves into the inner groove of the record being played.

While there has been described what is at present considered the preferred embodiment of the invention, it will be obvious to those skilled in the art that various changes and modifications may be made therein without departing from the in-

vention, and it is, therefore, aimed in the appended claims to cover all such changes and modifications as fall within the true spirit and scope of the invention.

5. What is claimed is:

1. In an automatic phonograph having record-changing apparatus for handling records of relatively small diameter and relatively large diameter, a turntable and a pickup arm with a stylus for reproducing a record on said turntable, said pickup arm being adapted to move inwardly over said turntable and outwardly from said turntable, the combination comprising a means for controlling a record-changing cycle, a pickup arm control member having an aperture therein and engaging said means, means connected to said pickup arm and said pickup arm control member comprising a member within said aperture for engaging the walls thereof to control the movement of said pickup arm during a record-changing cycle, said aperture being of such size that it allows free movement of the pickup arm during the playing of a record, a 'stop' means positioned adjacent said pickup arm control member to limit the movement of said control member and said pickup arm when said pickup arm is moving inwardly with respect to said turntable during a record-changing cycle, a record support adjacent said turntable movable to a plurality of positions for supporting records of different diameters at their margins and means movable with said record support and engaging said stop means for moving said stop means in accordance with the position of said record support whereby said pickup arm may be moved inwardly to a predetermined position with respect to said record.
2. In an automatic phonograph having record-changing apparatus for handling records of relatively small diameter and relatively large diameter, a turntable and a pickup arm with a stylus for reproducing a record on said turntable, said pickup arm being adapted to move inwardly over said turntable and outwardly from said turntable, the combination comprising a cam means for controlling a record-changing cycle, a pickup arm control lever having an aperture therein and engaging said cam means, means connecting said pickup arm and said control lever comprising a member within said aperture for engaging the walls thereof to control the movement of said pickup arm during a record-changing cycle, said aperture being of such size that it allows free movement of the pickup arm during the playing of a record, a stop means positioned adjacent said pickup arm control lever to limit the movement of said control lever and said pickup arm when said pickup arm is moving inwardly with respect to said turntable during a record-changing cycle, a record support adjacent said turntable movable to a plurality of positions for supporting records of different diameters at their margins and means movable with said record support and engaging said stop means for moving said stop means in accordance with the position of said record support whereby said pickup arm may be moved inwardly to a predetermined position with respect to said record.
